UNITED STATES PATENT OFFICE.

JOSEPH P. EVANS, OF BIRMINGHAM, ALABAMA, ASSIGNOR, BY DIRECT AND MESNE ASSIGNMENTS, TO EVANS FUEL SAVING COMPANY, A CORPORATION OF ALABAMA.

METHOD FOR PREVENTING THE LOSS OF FUEL IN STARTING FURNACE-FIRES.

1,297,669.

Specification of Letters Patent. Patented Mar. 18, 1919.

Application filed April 23, 1918. Serial No. 230,208.

To all whom it may concern:

Be it known that I, JOSEPH PRIESTLEY EVANS, a citizen of the United States of America, residing at Birmingham, in the 5 county of Jefferson and State of Alabama, have invented certain new and useful Improvements in Methods for Preventing the Loss of Fuel in Starting Furnace-Fires, of which the following is a specification.

10 My invention relates to a method and apparatus for the prevention of loss of fuel when fires are started in locomotive and stationary boilers which have a top draft fire box.

15 According to the present practice, before starting a fire in a boiler fire box, the grate is cleaned so that it can be inspected and, in all top draft fire boxes, the fire is then started by spreading a layer of coal five or 20 six inches deep on the grate, laying kindling on top of the coal, opening the top drafts, and igniting the kindling. Where small sized coal is used, I have observed that a substantial percentage of the coal falls through 25 the grate into the ash pit and is lost while this initial bed of coal is being spread on the cleaned grate. With run-of-mine bituminous coal there is an average loss of about 250 pounds of coal in the starting of each 30 fire on a locomotive grate that is in perfect condition, but where fingers of the grate are broken off or portions of the table segments are missing, the wastage of coal will be as high as a ton in starting each fire.

35 The object of my present invention is to prevent this loss of fuel by a simple and inexpensive expedient which consists in laying over the grate surface a sheet or mat of paper, woven fiber or grass, or any combustible material which is comparatively cheap and which will prevent the fine coal falling through its meshes and wasting through the grate. This sheet or mat becomes ignited and is consumed as soon as the initial bed of 40 coal commences to burn freely, and when this takes place this coal becomes sufficiently coked to hold together and prevent loss of fuel while the fire is going.

As illustrative of my invention, I show in the drawings a perspective view, broken 50 away, of a locomotive boiler fire box with my invention in service.

As illustrated, the fire box 1 is typical of any top draft fire box having a fuel door 2 with top draft inlet ports 3 therein, a grate 55 4 of any standard type, and an ash pit 5.

In carrying my invention into effect, we will assume that the grate has been cleaned, as is customary, and is ready for a new fire to be started thereon. I first place in the 60 fire box and spread over the surface of the grate 4 a sheet or mat 6 of some cheap and inexpensive combustible material, such as coarse paper, mats woven of grass or like material. This sheet will substantially 65 cover the grate surface and will be supported thereby. The coal 7 is then introduced and spread on top of the sheet 6 to the desired thickness, kindling is laid on the coal, the top draft ports 3 are opened, and 70 the kindling is ignited. As it burns, it ignites the coal on top and as the latter burns it cokes into a fire bed, the heat of which ignites and consumes the sheet 6. The sheet 75 6, therefore, will not interfere with the normal updraft through the grate which is called into play as the fire is built up.

I do not desire to be limited to any particular material for the grate covering sheet, as it may be of any substance which is cheap, 80 which will hold the slack coal in place on the grate until it can coke, and which will be consumed when the fire is well started. My covering sheet can be readily applied at a cost of a few cents per fire started thereover, 85 whereas the present wastage of fuel, per fire started, will run from twenty-five cents to three and four dollars, depending on the cost of the fuel and the type and condition of the grates. Moreover, my invention will 90 save much expense in grate repairs heretofore necessary before a fire could be started on a defective grate, and I avoid the danger of the waste coal becoming ignited in the ash pit, which invariably results in burning 95 up the grate or seriously damaging it.

Having thus described my invention, what I claim as new and desire to secure by Letters Patent, is:—

The herein-described method of preventing the loss of fuel in starting fires on boiler grates having a top draft, which consists in substantially covering the grate surface with a sheet of combustible material adapted to

prevent the fine coal falling therethrough, laying the initial bed of coal on this sheet ¹⁰ and causing the bed of coal to burn from the top downwardly toward said sheet.

In testimony whereof I affix my signature.

JOSEPH P. EVANS.
